UNITED STATES PATENT OFFICE

2,664,730

CLOTHES-WASHING MACHINE

William Charlton Bell, London, and Victor Alfred Graham Curry, Greenford, England, assignors to Hoover (Washing Machines) Limited, Perivale, England, a company of Great Britain

Application February 10, 1948, Serial No. 7,378

1 Claim. (Cl. 68—131)

1

This invention relates to washing machines of the kind intended primarily for washing household clothes, fabrics and the like and comprising a container or "tub" adapted to contain washing liquid, i. e. water with or without soap or other ingredients to assist washing, and an impeller within the container arranged to be operated by suitable hand or power-driven driving mechanism so as to agitate the contents of the container.

The invention is primarily applicable, although not limited to a washing machine having a continuously rotating impeller mounted in or adjacent to a side wall of the container where it will normally be submerged in the washing liquid, and comprising a disc the whole periphery of which lies close to the side wall of the container.

Various forms of "tub" or container are known including some of rectangular cross-section in a plane at right angles to the horizontal impeller axis and some with a generally semi-circular bottom portion in such a plane.

It has now been found that a form of "tub" which is both convenient and efficient is one of generally rectangular form having one corner cut off along a lower edge parallel to the axis of the impeller. Hence, in accordance with the invention a washing machine comprises a container for washing liquid having a continuously rotating impeller mounted with its axis substantially horizontal in or adjacent to a side wall of the container, in which the container is of generally rectangular form, but has one corner cut off along a lower edge parallel to the axis of the impeller.

In some cases both corners along both lower edges parallel to the axis of the impeller may be cut off, but in general it is preferred that only one corner should be cut off, and that the direction of rotation of the impeller should be such that the lowest part of the impeller disc moves away from the corner which is cut off.

The manner in which the container is constructed may be settled by convenience. If desired a rectangular container may be employed having a wedge-shaped corner piece or a sloping partition inserted in it either to exclude liquid from the corner or simply to prevent clothes from lodging in the corner. Alternatively, the container may be initially formed so that its external shape as well as its internal shape has its corner cut off.

The invention may be carried into practice in various ways, but one specific embodiment will now be described by way of example, with reference to the accompanying drawings in which

2

Figure 1 is a side elevation of a container for a washing machine;

Figure 2 is an end elevation of the container of Figure 1, and

Figure 3 is a plan view of the container of Figure 1.

The washing machine container 10 shown in the drawings is shaped generally in the form of a rectangular solid and comprises end and side walls 11 and 12 respectively and a bottom 13. For manufacturing purposes, the container is built up from three pieces of sheet metal, a parallel-sided strip being bent to form a generally U-shaped centre panel forming the two end walls 11 and the bottom 13, and two side panels each forming a side wall 12. The two side panels are pressed so as to provide rounded corners at the interior ends of the container, and their edges are bent over at right angles to form flanges 14 which are welded to corresponding flanges 14¹ of the centre panel. The flanges are suitably soldered to produce watertight seams. A frame 15 of channel section fits over the top edges 16 of the panels, as shown in Figures 1 and 2.

One of the side walls 12 is pressed out to form a circular dish-like recess 17 in the lower part of the container. An electrically driven unidirectionally rotating impeller 18 is mounted in the recess 17 with its axes perpendicular to the side wall 12. The impeller 18 rotates clockwise as viewed in Fig. 1.

Between the right hand end wall 11 and the bottom 13 the wall of the container slopes toward the axis of the impeller 18 to form an inner inclined face 19 sloping downwardly and inwardly at a substantial angle of about 45° to the horizontal so that no pocket is formed in which clothes might be trapped. It is to be noted that the distance between the face 19 and the periphery of the impeller 18 decreases in the direction of rotation of the impeller so that fabrics or clothes being rotated therewith will tend to rotate upwardly against the face of the impeller rather than be trapped in a corner between the bottom 13 and the right hand wall 11.

The remaining part of the bottom 13 of the container is arranged to slope upwardly very slightly when the sides of the container are vertical, and at the lowest point, between the bottom 13 and the face 19, a drain hole 20 is provided, surrounded by an external flange 21 over which fits an elbow 22. A drain hose 23 is attached at one end to the elbow 22 and its other end is normally supported above the level of the liquid in the container by a hose clip or bracket 24 welded to the side wall 12 of the container. With the hose

thus supported no liquid will escape from the container, the joints between the flange 21, the elbow 22 and the hose 23 being watertight. In order to drain the container it is only necessary to detach the upper end of the hose from its clip, lower it below the level of the liquid in the container.

A bracket 25 bolted to the sides of the container close to the top, as shown in the drawings, serves to stiffen the structure and acts as a convenient ledge on which a wringer may be mounted if required.

Mounting lugs 26 on the outside of the container form a means of attaching it to a suitable stand.

The sloping face 19 of the bottom may be formed with a number of ribs or grooves running longitudinally along the face. Such ribs or corrugations, of which there may, for example, be three, may be comparatively shallow, but are sufficient to cause some resistance to motion of the clothes passing them, thereby causing the bundle of clothes to turn about its own axis at the same time as it is being bodily carried round the axis of the impeller under the influence of the impeller. The ribs may extend longitudinally along the inclined face or alternatively, they may extend obliquely, for example at 45° to the length of the inclined face.

What we claim as our invention and desire to secure by Letters Patent is:

A washing machine comprising; an open topped container shaped in general form of a rectangular solid; said container having a pair of parallel side walls in the form of irregular pentagons; a continuously rotating impeller mounted for rotation in one of said side walls on a horizontal axis on the vertical median line of said one side wall with said impeller lying closely adjacent thereto and toward the bottom thereof; each of said side walls having a top horizontal edge extending from front to rear of said container, a rear vertical edge extending from top to bottom of said container, a bot-

tom substantially horizontal edge extending from the rear edge to a point slightly past the median line of said side walls, a front vertical edge extending from the top edge to a point substantially level with the axis of said impeller, and a front downwardly and rearwardly substantially straight inclined edge extending from the lower end of said front vertical edge to the front end of said lower edge; said container having rear, bottom and front walls secured to the edges of said side walls and extending downwardly along said rear edges, forwardly along said bottom edges, upwardly and forwardly along said front inclined edges and upwardly along said vertical front edges; said impeller being rotated in a direction such that its periphery moves away from said front inclined edges toward said bottom edges and then toward said rear edges; said container being adapted to contain a cleansing liquid to a level above said impeller.

WILLIAM CHARLTON BELL.
